H. A. CARPENTER & A. W. WARNER.
MEANS FOR CONTROLLING THE OPERATION OF GAS RETORTS.
APPLICATION FILED JUNE 2, 1914.

1,112,978.

Patented Oct. 6, 1914.

UNITED STATES PATENT OFFICE.

HENRY A. CARPENTER AND ARTHUR W. WARNER, OF SEWICKLEY, PENNSYLVANIA,
ASSIGNORS TO RITER-CONLEY MANUFACTURING COMPANY, OF PITTSBURGH,
PENNSYLVANIA, A CORPORATION OF NEW JERSEY.

MEANS FOR CONTROLLING THE OPERATION OF GAS-RETORTS.

1,112,978.

Specification of Letters Patent.

Patented Oct. 6, 1914.

Application filed June 2, 1914. Serial No. 842,411.

To all whom it may concern:

Be it known that we, HENRY A. CARPENTER and ARTHUR W. WARNER, citizens of the United States, residing at Sewickley, 5 in the county of Allegheny and State of Pennsylvania, have invented certain new and useful Improvements in Means for Controlling the Operation of Gas-Retorts, of which the following is a specification.

- 10 Those manipulations of gas making retorts, such as charging and discharging, involving the opening and closing of the retort at its front and rear ends necessitate coöperation of the attendants at opposite 15 ends of the bench. The manipulations are usually carried out at the front or charging end, and for charging and discharging which are ordinarily accomplished by one and the same inward movement of a scoop 20 or charging tool it is necessary to open or clear the rear end. Under the present practice accidents are not uncommon due to the forward or entering movement of the tool before the rear end has been opened, 25 or before the rear operative is out of the way, resulting in damage to the apparatus, or injury to the workmen, or both, depending on the conditions existing when a premature operation takes place.
- 30 The primary object of the present invention is to forestall accident by controlling the retort-entering movement of the tool at both ends of the retort instead of only the front end as heretofore, rendering 35 it impossible for the tool to advance even though everything is in readiness at the front end until the operator at the rear end has actuated a controlling device, movement of which is necessary before the tool can 40 advance. The necessary rear end adjustment may be accomplished with the operator out of the range of the retort before the requisite adjustments have been made at the front end, in which case the "setting" 45 of the rear controller will not alone accomplish the forward movement, the mechanism remaining inactive until the front controller is also set. Conversely, the "setting" of the front controller will have 50 no effect until the rear controller has been set. Thus, the controllers coöperate and are dependent on each other for accomplishing the advancing movement of the tool, thereby preventing premature operation.

As here shown, the invention embodies 55 an electric circuit which controls the tool operating motor, with controllers in the circuit at both the charging and discharging ends of the retort, both controllers being necessarily thrown or set before the motor 60 can advance the tool. Provision is also had for automatically releasing the controllers so that they may return to normal position after the tool has started on its forward movement.

65 The retort entering tool is ordinarily carried by the retort charging machine which moves on a track along the front of a bench for operating on different retorts, and at the rear or discharge end a similarly movable gas producer charger is employed for delivering coke from the retorts into gas producers. The retort charger at one side of the bench and producer charger at the opposite side are each motor driven, and a 70 further purpose of the present invention is to render the motors thereof inoperative when the controllers above referred to are in set position. This is desirable for the producer charger as thereby after having 75 been properly positioned relatively to a retort such position cannot be disturbed prior to entering the tool in the retort. And with the controller in set position at the discharge end of the retort the producer charger cannot be moved, the operator at such end thereby necessarily knowing that a tool operation is impending and avoiding premature or untimely movement of the producer 80 charger.

85 A form of apparatus embodying the invention is illustrated diagrammatically in the accompanying drawing. Referring thereto, 2 designates a bench, and 3 is one of a series of retorts therein which is 90 adapted to open through the front and rear faces of the bench in the customary way. Removable closures, not shown, of usual or any preferred construction are provided for the front and rear ends of the retort.

- shaft 9 which extends through a nut or head 10 on the earring, shaft 9 being geared at 11 to an electric motor 12. Also geared at 13 to shaft 9 is a screw shaft 14, rotation of which slides contact bar 15 relatively to certain circuit terminals as will be presently explained. An electric motor 16 operates to move the retort charging machine on its track 5.
- 10 At the discharge side of the bench, 17 indicates gas producers surmounted by track 18 on which moves the producer charging machine 19 which may be propelled by an electric motor 20.
- 15 The mechanism as here shown is embodied in a three-phase electric system, having three conductors A, B and C for the retort charging machine which, respectively, are engaged by the trolleys *a*, *b* and *c* carried by the latter. Three like conductors A', B' and C' are, respectively, engaged by trolleys *a'*, *b'* and *c'* carried by the producer charger. Conductors A and A', B and B', C and C', are, respectively, pairs or branches of the three main conductors D, E and F.
- 20 G and G', H and H' are two pairs of dummy conductors with those of each pair connected. Engaging conductors G and H, respectively, are the trolley contacts *g* and *h* carried by retort charging machine 4, and similar trolley contacts *g'* and *h'* carried by the producer charger 19 engage, respectively, conductors G' and H'.
- 25 A double or reversing switch 25 directs the current to motor 12, the current for the forward movement being controlled by solenoid 26 and for the backward movement by solenoid 27. This double solenoid switch is of usual and well known construction.
- 30 The wiring for motor 12 and switch 25 is as follows: Wire 28 from trolley *a* leads to switch 25; wire 29 from trolley *b* to switch 25; and wire 30 from trolley *c* to motor 12, a branch 30' of wire 30 extending to the charging machine travel motor 16. The circuit 31 for the "forward" solenoid 26 extends across the traveling contacts *h* and *h'* to interruption 32 of controller X carried by the producer charger 19, and from thence by line 33 to trolley *b'*. The other line 34 for solenoid 26 extends to an interruption 35 on hand switch Z carried by the charging machine 4, thence to interruption 36 of controller Y also carried by said machine, thence to contact arm 37, through contact bar 15 to contact arm 38, the latter uniting with line 30 leading to trolley *c*. Thus it will be seen that to close the circuit through "forward" solenoid 26, interruptions 32 and 36 located, respectively, at the rear and front of the retort must be closed. For interruption 32 this is accomplished by blade 39 of the pivoted arm 40 of controller X, and at the front 45 by similar blade 41 of pivoted arm 42 of controller Y. Blade 39 is adapted to be held in circuit-closing position against the pull of spring 43 by pivoted latch 44 connected to the core of solenoid 45. And similarly, blade 41 is held in circuit-closing position by a latch 46 secured to the core of solenoid 47. Thus, with controller arms 40 and 42 secured by their respective latches as described, with interruptions 32 and 36 closed by blades 39 and 41, respectively, and with the hand switch Z turned to close interruption 35, the circuit is closed through "forward" solenoid 26 and hence switch 25 is operated to so direct the current to motor 12 as to advance tool 7 into the retort. But this cannot be accomplished until after controller X has been properly set at the discharge end of the retort after the operator has that end in readiness, nor can it proceed until controller Y has been latched back by the charger operator after everything is in readiness at the front or charging end of the retort. Solenoids 45 and 47 operate to automatically release the controller arms 40 and 42, respectively, permitting them to move to the positions shown in the drawing, when the tool 7 has reached the forward limit of its travel. These solenoids are arranged in two branches at one side 48 of the solenoid operating circuit, the branches joining at 48', with one branch 49 extending through solenoid 47 and from thence by line 49' to line 29 leading to trolley *b*. The other branch 50' extends through the traveling contacts *g* and *g'*, and thence through line 51 and solenoid 45 with the opposite end of the latter connected by line 51' with line 33 leading to trolley *b'*. From junction point 48' circuit 48 extends to the contact 52 which is engaged by bar 15 when in lowermost position, *i. e.*, with tool 7 fully projected into the retort, and with bar 15 making connection between contact 52 and contact arm 38 which is connected by line 30 of trolley *c*, the circuit for solenoids 45 and 47 is energized and the resulting elevation of their cores releases the controller arms 40 and 42, thereby opening the controller circuit at 32 and 36.
- 55 The circuit 55 for the "backward" or reversing solenoid 27 extends from the latter to switch 25, thence by motor circuit line 29 to trolley *b*. The line 55 from the opposite end of said solenoid extends to interruption 35' of controller Z and thence by line 56 to contact arm 57 and to the traveling bar 15, across the latter and through arm 38 and line 30 to trolley *c*. Thus, when pivoted arm Z' of hand switch Z is moved to the position shown in the drawing and bridging interruption 35', the circuit through solenoid 27 is closed and switch 25 is operated to reverse motor 12 and withdraw tool 7.
- 60 In the position of the parts shown in the drawing, tool 7 has completed its forward 130

travel into the retort and is being withdrawn therefrom, contact bar 15 rising from its lowermost position. It will be understood that the gearing which synchronizes the movement of screw shafts 14 and 9 places bar 15 in its lowermost position when tool 7 has been fully entered in the retort, at which time the circuit through solenoids 45 and 47 is closed as heretofore explained, thereby automatically releasing the latches 44 and 46 and deenergizing the "forward" solenoid 26. The arrangement is preferably such that the circuits for operating the travel motors 16 and 20 are controlled by the controllers X and Y in such manner that when the latter are latched back preparatory to advancing tool 7 into the retort, neither the retort charging machine nor the producer charger can be moved. The circuits for motors 16 and 20 may be readily traced to their respective trolley contacts through the two interruptions 58 and 58' at controller Y, and similar interruptions 59 and 59' at controller X, the interruptions 58 and 58' being bridged by arm 42 of controller Y, and the blade 60 of arm 40 of controller X similarly bridging interruptions 59 and 59'. Thus, while the travel motors are inoperative so long as controllers X and Y are held by the latches, they are each fully operative as soon as the arms are released. The direction of travel of the retort charging machine may be determined by the reversing switch 61, and a similar switch 62 may be provided for the circuits leading to motor 20 of the producer charger.

We claim:

1. In gas generating apparatus, the combination of a retort adapted to be charged at one end and discharged at its opposite end, a tool adapted to enter the retort, a tool actuating motor, and conjointly operating motor controlling devices at opposite ends of the retort.
2. In gas generating apparatus, the combination of a retort adapted to be charged at one end and discharged at its opposite end, a tool actuating motor, and motor controlling devices at opposite ends of the retort and operatively connected to each other and to the motor for conjointly controlling the retort-entering movement of the tool.
3. In gas generating apparatus, the combination of a retort adapted to be charged at one end and discharged at its opposite end, a tool actuating electric motor, an electric circuit for the motor, and controllers for the circuit located at opposite ends of the retort.
4. In gas generating apparatus, the combination of a retort adapted to be charged at one end and discharged at its opposite end, a tool actuating electric motor, a motor circuit, an electrically operated device for
5. In gas generating apparatus, the combination of a retort adapted to be charged at one end and discharged at its opposite end, a tool adapted to be entered in the retort, a tool actuating electric motor, a controlling circuit for the motor extending to and having interruptions at opposite ends of the retort, and circuit closing devices at opposite ends of the retort and adapted to be separately operated to close said interruptions.
6. In gas generating apparatus, the combination of a retort adapted to be charged at one end and discharged at its opposite end, a retort charging machine and a producer charger movable respectively relatively to opposite ends of the retort, a retort entering tool and a tool actuating motor mounted on the charging machine, conductors, a motor operating circuit having traveling contacts for the conductors, a motor controlling circuit extending to and having interruptions at the retort charging machine and producer charger, and separately operated circuit closing devices for said interruptions.
7. In gas generating apparatus, the combination of a retort adapted to be charged at one end and discharged at its opposite end, a retort charging machine and a producer charger movable respectively relatively to opposite ends of the retort, traction motors for the charging machine and producer charger, conductors, interrupted circuits for the traction motors having traveling contacts for the conductors, a retort entering tool and a tool actuating motor mounted on the charging machine, a controlling circuit for the tool actuating motor with said circuit extending to and having interruptions at the charging machine and producer charger, and controlling devices on the charging machine and producer charger, respectively, each controlling device being common to one of the traction motor circuit interruptions and an interruption of said controlling circuit and with each device adapted in one position to close one of said circuit interruptions and open the other interruption and in another position adapted to close the previously open interruption and open the previously closed interruption.
8. In gas generating apparatus, the combination of a retort adapted to be charged at one end and discharged at its opposite end, a retort entering tool and a tool actuating motor, a circuit for the motor extending to and having interruptions at opposite ends of the retort, controlling devices separately operated to close the circuit inter-

opening and closing the motor circuit, a controlling circuit for actuating said device, and conjointly operating controllers for the controlling circuit located at opposite ends of the retort.

70

5. In gas generating apparatus, the combination of a retort adapted to be charged at one end and discharged at its opposite end, a tool adapted to be entered in the retort, a tool actuating electric motor, a controlling circuit for the motor extending to and having interruptions at opposite ends of the retort, and circuit closing devices at opposite ends of the retort and adapted to be separately operated to close said interruptions.

75

6. In gas generating apparatus, the combination of a retort adapted to be charged at one end and discharged at its opposite end, a retort charging machine and a producer charger movable respectively relatively to opposite ends of the retort, a retort entering tool and a tool actuating motor mounted on the charging machine, conductors, a motor operating circuit having traveling contacts for the conductors, a motor controlling circuit extending to and having interruptions at the retort charging machine and producer charger, and separately operated circuit closing devices for said interruptions.

80

7. In gas generating apparatus, the combination of a retort adapted to be charged at one end and discharged at its opposite end, a retort charging machine and a producer charger movable respectively relatively to opposite ends of the retort, traction motors for the charging machine and producer charger, conductors, interrupted circuits for the traction motors having traveling contacts for the conductors, a retort entering tool and a tool actuating motor mounted on the charging machine, a controlling circuit for the tool actuating motor with said circuit extending to and having interruptions at the charging machine and producer charger, and controlling devices on the charging machine and producer charger, respectively, each controlling device being common to one of the traction motor circuit interruptions and an interruption of said controlling circuit and with each device adapted in one position to close one of said circuit interruptions and open the other interruption and in another position adapted to close the previously open interruption and open the previously closed interruption.

100

8. In gas generating apparatus, the combination of a retort adapted to be charged at one end and discharged at its opposite end, a retort entering tool and a tool actuating motor, a circuit for the motor extending to and having interruptions at opposite ends of the retort, controlling devices separately operated to close the circuit inter-

- ruptions, and means actuated by the tool motor for causing said circuit interruptions to be opened.
9. In gas generating apparatus, the combination of a retort adapted to be charged at one end and discharged at its opposite end, a retort charging machine and producer charger movable respectively relatively to opposite ends of the retort, electric motors for moving the charging machine and producer charger and interrupted circuits for said motors, a retort entering tool and a tool actuating motor mounted on the charging machine, a controlling circuit 15 for the tool motor with said circuit extending to and interrupted at the charging machine and producer charger, a spring-actuated controller common to an interruption in the controlling circuit and to the interruption in the circuit of the motor for moving the charging machine and adapted normally to close the last mentioned circuit interruption and open the controlling circuit interruption, a spring actuated controller 20 common to an interruption in the controlling circuit and to the interruption in the circuit of the motor for moving the producer charger and adapted normally to close the last mentioned circuit with the interruption in the controlling circuit open, devices for holding the controllers out of normal position and closing the controlling circuit interruptions and with the circuits for the 25 motors of the charging machine and producer charger open, and means made operative by the tool actuating motor for releasing said controller holding devices.
10. In gas generating apparatus, the combination of a retort, a tool adapted to enter the retort, a tool actuating motor, a controlling circuit for the motor extending to and having interruptions at opposite ends of the retort, means for moving the tool to and from retort-entering position, a traction motor for the tool-positioning means, 40 a traction motor circuit, a controller common to the traction motor circuit and to one of the interruptions of the tool-controlling circuit, and means for closing the other interruption of the tool-controlling circuit. 50
11. In gas generating apparatus, the combination of a retort, a producer charger and a retort-entering tool located, respectively, at opposite ends of the retort, a tool actuating motor, a controlling circuit for said 55 motor extending to and having interruptions at opposite ends of the retort, a traction motor for the producer charger, a controller common to the traction motor circuit and to one of the interruptions of the tool-controlling circuit, and means for closing the other interruption of the tool-controlling circuit.

In testimony whereof we affix our signatures in presence of two witnesses.
